VENTILATING HOOD FOR COOKING RANGES

Irving Herman, North Hollywood, Calif.

Application February 6, 1956, Serial No. 40,642

Term of patent 14 years

(Cl. D81—25)

Fig. 1.

Fig. 2.

Fig. 3.

Fig. 4.

Figure 1 is a perspective view of the ventilating hood for cooking ranges, showing my new design; Figure 2 is a top plan view of the ventilating hood; Figure 3 is a front view of the ventilating hood; and Figure 4 is an end view of same.

I claim:

The ornamental design for a ventilating hood for cooking ranges, as shown.
